UNITED STATES PATENT OFFICE

SYLVANUS D. LOCKE, OF BRIDGEPORT, CONNECTICUT, ASSIGNOR TO THE LOCKE STEEL CHAIN COMPANY, OF BRIDGEPORT, CONNECTICUT, A CORPORATION OF CONNECTICUT

APPARATUS FOR MAKING CHAIN

Application filed August 24, 1926. Serial No. 131,233.

This invention relates to an apparatus for and a process of making chain links and assembling the same, and pertains essentially to the manufacture of sheet metal drive chains.

The invention presents general and specific improvements over the disclosures of structures such, for example, as that of the patent to Osswald, No. 1,107,831, granted August 18, 1914. In said patent, the specific apparatus illustrated and described contemplates successive operations upon strip metal to provide nearly completed chain links integral with the strip, severance of the nearly completed chain links from the strip, and connection of each severed link to a continuously increasing strand of chain. While apparatus such as that of the patent to Osswald identified is efficient in practice in the production of chain links and chain, great care must be exercised to insure that the different sets of working elements which successively act upon the strip metal and its integral, partially completed links are properly situated relatively to each other, and to insure that there will be exact registration with the working elements of the whole of the length of the strip metal and said integral, partially completed chain links. Furthermore, when utilizing apparatus such as that of the Osswald patent identified to make chain, there is wasted from each coil a length or strip of uncompleted links usually amounting to several blanks and a small length of unworked steel, and to prevent additional waste it is necessary to feed the metal strip by hand after it leaves the feed jaws. In starting operations upon a strip a few links are wasted before the newly started operations become properly located on the dies. After a strip is fed to the first operation by hand, it is fed by power to the other operations, but several links must be discarded before a perfect one is formed, owing to the fact that each operation influences the location of the blank on the other operations, and until a link is made from a blank started after a complete set of operations is made the links will be imperfect.

An important object of the present invention is to provide an apparatus for and a

process of successively transforming metal stock into connected chain links wherein each transforming operation (or desired segregated series of operations) is performed practically independently of all other operations (or segregated series of operations), whereby the situating of the different sets of working elements to successively act upon the stock in proper relation to each other and the accomplishment of the necessary registration of the stock with said working elements are greatly facilitated.

A further important object is to provide an apparatus for and a process of making chain links which contemplate the successive severance of individual blanks from a strip of metal, and the performance of successive transforming operations upon each severed blank to produce a chain link, whereby to make just as good a link from the first blank as from any other blank, to properly complete every blank which is started, and to more easily and accurately locate each blank during the different transforming operations.

Another important object is to provide an apparatus for and a process of making connected chain links which contemplate the successive severance of blanks, one by one, from a strip of metal, the performance of successive transforming operations upon each severed blank to produce a nearly completed chain link and the successive connection of each nearly completed link to a continuously increasing strand of chain.

Another important object is to provide an apparatus for and a process of making chain links and connecting them, which contemplate the successive severance of blanks from a strip of metal, the performance of successive transforming operations upon each severed blank to produce a nearly completed chain link, the performance of each successive operation (or segregated series of operations) being independent of all other operations (or segregated series of operations), and the successive connection of each nearly completed link to a continuously increasing strand of chain.

Another important object is to provide an apparatus for and a process of making chain wherein the bending, shaping and forming

elements for performing each operation (or segregated series of operations) in the production of chain are self-contained and easy to adjust without reference to bending, shaping and forming elements for performing other operations (or segregated series of operations), the working elements of the present apparatus and process being simpler than the working elements of apparatuses such as that of the Osswald patent identified wherein each working element is attached to the others, and having great advantage over working elements or dies operated on different and independent presses, there being no danger, when utilizing the present apparatus to practice the improved method, of making up a large batch of one operation and later finding that these are not properly formed to suit other operations.

Another important object is to provide an apparatus for and a process of successively performing transforming operations upon metal blanks to produce connected chain links, contemplating the utilization of working elements for each chain link producing operation (or segregated series of operations) which are practically independent of the working elements for all other chain link producing operations (or segregated series of operations), and also contemplating the presentation of each blank successively and at once to each of the working elements for performing all of the chain producing operations, whereby imperfections can be immediately detected, as in the case of apparatuses such as that of the Osswald patent identified, a distinct improvement over dies operated on independent presses, and whereby to produce more accurate links with less trouble and care than necessary when utilizing an apparatus such as that of Osswald.

45 Another important object is to provide an apparatus for and a process of making chain links each having side bars and curvilinear end bars, which contemplate the severance of blanks, one by one, from a strip of metal, and the performance of successive and independent link producing operations upon each 50 severed blank, whereby to more easily form both of said curvilinear end bars. It seems impossible to nicely balance the operation of shaping the curvilinear end bars of a link unless the shaping is done after the link is 55 severed from the strip.

Another important object is to provide an apparatus for and a process of making chain links and assembling them which contemplates the severance, one by one, from a strip of metal, of blanks, the feeding of each blank, step by step, from station to station in the machine, and the performance at each station of a chain link producing operation (or segregated series of operations) upon each blank.

65 Another important object is to provide im-

the apparatus an improved and novel severed-chain-link-blank feeding and positioning mechanism.

Another important object is to provide in the apparatus a severed-chain-link-blank feeding and positioning mechanism including a transfer slide and devices for ejecting the blanks from the dies and situating said blanks in position to be carried ahead step by step, from work station to work station, by the slide. 70 75

Another important object is to provide in the apparatus an improved and novel feeding and positioning mechanism for the severed link blanks which is adapted to cooperate with ordinary devices heretofore utilized to feed the strip metal to the apparatus and the finished chain out of the machine. 80

Another important object is to provide in the apparatus mechanism for feeding the strip metal; the severed links, and the finished chain, together with mechanism for stretching or sizing the links as completed by the apparatus. 85

Another important object is to provide an apparatus wherein the feeding of the severed blanks from work station to work station is accomplished in such manner as to insure that there will be exact registration between each severed blank and the working elements at each of said stations. 95

Other important objects are to provide a novel construction of mechanism in the apparatus for successively severing, one by one, chain link blanks from a strip of metal; to provide novel working elements for successively receiving and operating upon each blank whereby the blank is progressively transformed into a chain link; and to provide novel and improved mechanism for actuating all of the operating parts of the apparatus in synchronism. 100 105

Other objects and advantages will become apparent from the drawings and description of construction and operation of a machine embodying the invention herein selected for the purpose of illustration.

Fig. 1 is a front elevational view, partly broken away, of a machine illustrating one way of carrying out the invention, the improved apparatus being incorporated in the machine:

Fig. 2 is a view partly in side elevation and partly in section of the strip feed mechanism on the machine; 120

Fig. 3 is a front view of a portion of the strip feed mechanism, detached;

Fig. 4 is an enlarged view of the dies, showing them in section and in engagement with blanks of metal, the sizing mechanism and the extractor mechanism also being disclosed; 123

Fig. 5 is a view corresponding with the disclosure of Fig. 4, but showing the dies spaced apart and the strip, incompletely chain links, and connected chain as ready to be fed ahead 130

one step, the dies for the sake of clearness being further apart than they would be with the strip, links and chain in the positions disclosed;

5 Fig. 6 is a bottom plan view of the upper dies;

Fig. 7 is a top plan view of the lower dies;

Fig. 8 is a sectional view as on line 8—8 in Fig. 6 or Fig. 7.

10 Fig. 9 is a sectional view as on line 9—9 in Fig. 7, disclosing the carrier for the movable dies in side elevation, and the transfer slide actuating mechanism in the rearward position of said transfer slide;

15 Fig. 10 is a detail view disclosing the transfer slide actuating mechanism in the advanced position of said transfer slide;

20 Fig. 11 is an enlarged fragmentary front elevational view of the machine, partly broken away and in section, detailing the mechanism for elevating the link blanks from the lower dies;

Fig. 12 is a fragmentary elevational view as seen from the left in Fig. 11;

25 Fig. 13 is a bottom plan view of a part of the disclosure of Fig. 12;

Fig. 14 is an edge view of a strip of metal and incompletely blanks being formed into a chain, some formed and coupled links being shown; and

30 Fig. 15 is a plan view of the metal strip, incompletely blanks, and chain shown in Fig. 14, as viewed from the bottom of Fig. 14.

In the drawings, 1 indicates as an entirety 35 the main frame of the machine comprising uprights 2, 3, and a bed 4 arranged between the uprights.

35 Fig. 5 is a vertically reciprocatable slide mounted to move up and down in guides 6, 7, on the main frame.

40 Fig. 8 is a main drive shaft transversely mounted in bearings at the upper end of the frame. 9 is a countershaft transversely mounted upon the main frame and extending from one side to the other thereof. At one side of the main frame the counter shaft carries a loose pulley 10, a fast pulley 11, and a fly wheel 12. At the other side of the frame the said counter shaft has mounted loosely 45 upon it a pinion 13 carrying one element 14 of a clutch 14, the other element 14a of which is splined to the countershaft 9. Any suitable mechanism may be employed for throwing the longitudinally movable element 14a of said clutch into and out of engagement with the element 14', so as to transmit power through the pinion 13. 15 is a gear wheel rigidly secured to said main shaft and in mesh with the pinion 13.

45 Fig. 16 is an eccentric on the main shaft 8 connected by eccentric straps 17, 17' and pitman 18 to the slide 5.

50 Any suitable mechanism may be attached to the frame for feeding the stock or strip of metal from which the chain links are to be

formed to location above the bed or bolster of the press for the first operation upon said stock or strip of metal. For the purpose of illustration, I have, in the drawings, shown a feed mechanism of which 19 is a bracket secured to the standard 3 of the frame and having a horizontally disposed platform 20, the inner end of which extends into a hole 3' through the standard 3.

55 21, 21, are side walls extending vertically upward, one at each side of the platform 20. 22 is a horizontally reciprocatable slide suitably mounted at either side in guideways in the said side walls 21. It rests upon a horizontally disposed friction plate 23 having downwardly extending pins 24, 24, each surrounded by a coil spring 25 bearing at its lower end against the platform 20 so as to provide a yielding support for the slide 22 which normally tends to press the slide against the upper walls of its guideways to insure the closing of the feed jaws, to be hereinafter described, before the slide commences to move forward.

60 26 is a gripping piece carried by the slide 22, having an upwardly turned jaw 26' adapted to engage the under surface of the stock or strip of metal to be fed to the bed 4.

65 27 is an oscillatable gripping dog having a jaw 27' adapted to engage the upper surface of the strip of metal to be fed, at a point directly above the gripping jaw 26'. This gripping dog 27 is pivotally mounted between upwardly extending lugs or ears 22', 22' on the slide 22, and carries an upwardly extending arm 28.

70 29 is a bell crank lever pivotally connected at 29' between the side walls 21 of the bracket 19.

75 30 is a rod pivotally connected at 30' to the upper end of the arm 28, and at 30a to the free end of the arm 29a of the bell crank lever 29.

80 31 is an adjustable stop for limiting the throw of the arm 28 in clockwise direction. 110 This stop preferably consists of a screw extending through a threaded opening in a cross bar 22a, which latter extends between the ears 22', 22' on the slide 22.

85 32 is a crank disc carried by the main drive shaft 8 and having a crank pin 32' to which is pivotally connected one end of a connecting rod 33, the other end of which is suitably connected to the free end of the arm 29b of the bell crank lever 29.

90 34, 34, and 35, 35, are straightening rolls for the strip of metal or stock. These rolls are horizontally disposed and suitably mounted between the side walls 21, 21 on the bracket 19. A strip of metal, indicated by 36, is directed between the rolls 34, 34, and 35, 35 and between the gripping lips 26' and 27'. The dog 27 and arm 28 are shaped and proportioned to have a slight rocking motion relative to the slide 22, so that in normal op- 125

eration, as the connecting rod 30 is drawn to the right in Figs. 1 and 2, the gripping jaw 27' is rocked out of engagement with the upper surface of the strip of metal 36. The arm 28 then engages the stop 31 and the slide 22 recedes with the connecting rod 30. Upon the reversal of travel of the rod 30, it rocks forward the upper end of the arm 28 and causes the gripping jaw 27' to engage the upper surface of the strip 36, thereby gripping the said strip firmly between the jaws 26' and 27' and the slide 22 and strip 36 are together fed forward.

37 is a carrier or holder for the movable or upper dies, it being suitably connected to the slide 5, and 38 represents a die bed for the stationary or lower dies, said die bed 38 being secured upon the bed 4 in any suitable manner.

As disclosed, there are five sets of oppositely disposed dies, indicated 39, 40, 41, 42, and 43 respectively, each set consisting of an upper, movable die 44 and a lower, stationary die 45, and all of said dies 44, 45, are preferably arranged in longitudinal alignment with the line of feed of the strip 36 and are properly centered relative to the said line of feed. Each set of dies 39, 40, 41, 42 and 43 is adapted to accomplish a chain making operation (or segregated series of operations) to be performed in the machine. It is to be understood that a greater or less number of sets of dies can be utilized without departing from the spirit of the invention, and that the upper die 44 of each set is disposed directly opposite the lower die 45 of the same set.

Each die 44, 45 may be associated with the carrier 37 and die bed 38, respectively, in any suitable manner. As disclosed, each die 44 has a shank 46 fitted in an opening 47 in the carrier 37, and oppositely disposed flanges 48 upon the lower face of said carrier insure the set positions of said dies 44. The die 44 for cooperating with a die 45 for accomplishing the first operation, or segregated series of operations, to produce chain, is at slightly higher elevation than the remainder of said dies 44. The die bed 38 is recessed as at 49, and an anvil plate 50 rests upon said die bed 38 at the base of said recess. A block 51 within the recess 49 and upon the anvil plate has spaced openings 52 in which four of the dies 45 are suitably situated to rest upon said anvil plate. The remaining die 45, for cooperating with the corresponding die 44 for the first operation, or segregated series of operations, to produce chain, is suitably located in a smaller recess 53 of the die bed 38 and is at an elevation slightly above that of the dies 45 within said recess 49. It is apparent that each of the dies 44 and 45 is thus associated with the carrier 37, or the die bed 38, as the case may be, independently of all other dies.

The first set of dies, indicated 39, is, as disclosed, for the purpose of completely outlin-

ing each link blank. 54 are scoring knives or chisels arranged upon the upper die 44 of the set of dies 39, for the first operation, or segregated series of operations, adapted to impart lines of score to the upper surface 70 of the strip of metal, which lines are parallel in the direction of the feed of said strip. 55 is a scoring knife of said mentioned upper die 44 adapted to impart a line of score to the upper surface of the strip of metal, which line is at right-angles to the lines of score imparted by the knives or chisels 54, between said mentioned lines and not far from their rear ends. 56 is a scoring knife of said mentioned upper die 44 adapted to impart a transverse score to the strip of metal along the line of severance of two links which are to adjoin each other. 57 are corresponding scoring knives or chisels of the die 45 of said set 39 arranged to impart lines of score to the under surface of the strip of metal, each of which lines is directly beneath a line of score imparted by one of the upper scoring knives 54. 58 is a corresponding scoring knife or chisel of the die 45 of said set 39 arranged to impart a line of score to the under surface of the strip of metal, which line is directly beneath the line of score imparted by the upper scoring knife 55. 59 is a corresponding scoring knife or chisel of the die 45 of said set 39 arranged to impart a line of score to the under surface of the strip of metal, which line is directly beneath the line of score imparted by the upper scoring knife 56. It is to be understood that although the set of dies 39 as disclosed is adapted to completely outline each link blank before the same is severed from the strip of metal, stock to provide a blank could be severed from the strip in advance of any link producing operations whatever.

The lower die 45 of the set of dies 39 and the upper die 44 of the set of dies 40 are adapted to cooperate to sever the link blanks, one by one, at the score line made by the knives 56 and 59, from the strip of metal. To the accomplishment of this end said upper die 44 of the set 40 has a rearward transverse severing edge 60 adapted to cooperate with a forward transverse severing edge 61 of said lower die 45 of the set 39 in a manner which is clear in Figs. 4 and 5.

The set of dies, indicated 40, for performing the second operation, or segregated series of operations, for producing chain, is, as disclosed, essentially for the purposes of breaking the metal of each severed link blank along the line of score made by the scoring knives 55, 58, and along portions of the lines of score made by the scoring knives or chisels 54, 57 to define the long, narrow lip of the large end or sprocket bar of the link, and of removing said long, narrow lip slightly out of the plane of the link blank. It will be plain, however, that the set of dies 40, as well

as the other sets, could perform link transforming operations in a manner and a sequence different from the manner and sequence disclosed.

5 Of the lower or stationary die 45 of the second set of dies, 62 represents a severing and bending projection adapted to enter a depression 63 of the upper or movable die 44 of said second set 40. 64 is a transverse severing edge at the rear of said projection 62 adapted to cooperate with a transverse severing edge 65 of said upper die 44 of the second set and at the rear of said depression 63, to sever the metal along the line of score made by the scoring knives 55, 58. 66 indicate longitudinal severing edges of said bending projection 63 of the second set adapted to cooperate with longitudinal severing edges 67 of the upper die or depression 63 of said second set, to sever the metal along the portions of the lines of score made by the knives 54, 57 to define the long, narrow lip of the large end or sprocket bar. The outer or upper face 68 of the bending projection 60 is inclined slightly to cause the long, narrow lip of the large end or sprocket bar to be displaced upwardly a trifle from the plane of the metal blank when past the second set of dies. As will be evident from Figs. 4 and 5, the side bars of the link are held between the flat faces of the second set of dies while the working elements are operating.

35 The third set of dies, indicated 41, for performing the third operation, or segregated series of operations, for producing chain, may include the working elements for breaking the metal along portions of the lines of score made by the scoring knives or chisels 54, 57 to define the short, narrow lip of the small end bar or pintle, for bending, forming or shaping the small end bar or pintle to final curvilinear form, for bending, forming or shaping the short, wide lip of the large end or sprocket bar to final curvilinear form, and for preliminary bending, forming or crimping the long, narrow lip of said large end or sprocket bar.

40 Of the upper die 44 of the third set of dies, 69 denotes a crimping punch having a part-circle, preferably approximately half-circle, transverse convex crimping surface 70 adapted to cooperate with a complementary concave crimping surface 71 of the lower die 45 of said third set to bend, form, or shape the small end bar of a link blank to final, desirably half-circle configuration. As disclosed, the convex crimping surface 70 includes a rearward quarter-circle part 70' which is complementary to a rearward quarter-circle part 71' of the concave surface 71 in shaping the short, wide lip of the small end bar or pintle, and said crimping surface 70 includes a forward quarter-circle part 70a which is complementary to a forward quarter-circle part

71a of said surface 71 in shaping the short, narrow lip of said small end bar or pintle, the construction of the crimping surfaces 70 and 71 being such that both curvilinear lips of the small end bar or pintle are shaped upwardly from the plane of the strip of metal. See Figs. 4 and 5. The forward part of the punch 69 includes longitudinal severing edges 72 complementary to severing edges 73 of the lower die of said third set in severing the metal for the short, narrow lip of the small end bar or pintle along portions of the lines of score 54, 57 to define said short, narrow lip. The lower die 45 of the third set of dies has a concave crimping projection 74 in advance of the crimping surface 71, which is complementary to the convex crimping surface 75 of the upper die of the third set, the surfaces 74 and 75 desirably being of part-circle, preferably quarter-circle, configuration, and being adapted to together crimp the free end of the long, narrow lip of the large end or sprocket bar of the link, previously severed by the second set of dies. In advance of the surface 74 the lower die of the third set is inclined as at 76 to conform to the inclined surface 77 of the upper die of said third set, the inclination being about the same as that of the surface 68 of the lower die of the second set of dies, for an obvious purpose. In advance of the inclination 76 the lower die of the third set includes a concave part-circle crimping surface 78 adapted to cooperate with a complementary convex crimping surface 79 of the upper die of the third set to bend, form, or shape the short, wide lip of the large end or sprocket bar to final curvilinear form. As disclosed, the free end of the long, narrow lip and the short, wide lip of the large end or sprocket bar are crimped upwardly from the metal blank. Naturally, certain bending, forming and shaping surfaces which operate upon the narrow lips of the end bars must be of width to enter between the link side bars. As disclosed, all of the working elements are of width approximately equal to the distance between the side bars of the link being produced, except the crimping surfaces 71', 70' and 78, 79 which form the short, wide lips of the small end bar or pintle and the large end or sprocket bar, respectively. As in the case of the second set of dies, the flat faces of the upper and lower dies of the third set 41 engage the link side bars and thus cooperate in insuring the position of the link while the working elements of the dies are functioning. See Figs. 4, 5, 6 and 7.

45 The fourth set of dies, indicated 42, for accomplishing the fourth operation, or segregated series of operations, for producing chain, may include the working elements for positioning the small end bar or pintle of the link at desired and proper angle to the link side bars, and for throwing the short,

wide lip of the large end or sprocket bar downwardly and the long, narrow lip thereof further upwardly, to thus place the large end or sprocket bar in position for the final 5 or assembling operation. The final position of the small end bar or pintle as obtained in the fourth set of dies is, as disclosed, preferably approximately at right-angles to the link side bars, the short, narrow lip being thrown upwardly and the short, wide lip 10 being thrown downwardly by the dies of the fourth set. The short, narrow lip of the small end bar or pintle and the long, narrow lip of the large end or sprocket bar having 15 been severed from the side bars of each link before reaching the fourth set of dies, all that is necessary to throw the short, wide lips of the end bars downwardly below the plane of the link blank is to produce bends at the 20 opposite ends of each side bar, the downward throwing of the short, wide lips, naturally, causing the long, narrow lip of the large end or sprocket bar and the short, narrow lip of the small end bar or pintle to be 25 thrown upwardly.

Of the upper die 44 of the fourth set of dies, 80 are punches at the rear of die 44 adapted to cooperate with bending edges 81 of the lower die 45 of the fourth set to produce 30 bends in the rear ends of the link side bars to position the small end bar or pintle at right-angles to said side bars, the lower die being cut away as at 82 to allow clearance for the short, wide lip of said small end bar 35 or pintle. The punches 80 are spaced apart a distance about equal to the width of the short, narrow lip of the small end bar or pintle in order that said short, narrow lip can clear said punches during the bending 40 operation. The working faces 83 of said punches 80 are desirably of part-circle configuration, as are also the cut-away portions 82 of the lower die of the fourth set. During the bending operation the working faces 83 45 engage the inner face of the already formed short, wide lip of the small end bar or pintle, while the link side bars lie between flat surfaces 84 and 85 of the upper and lower dies, respectively, in such manner that the rear 50 ends of said link side bars are at said bending edges 81. 86 are somewhat similar punches at the front of the upper die 44 of the fourth set of dies adapted to cooperate with bending edges 87 of the lower die of the fourth 55 set to produce bends in the front ends of the link side bars to throw the short, wide lip of the large end or sprocket bar downwardly and thus position said large end or sprocket bar in its final assembling position. In advance 60 of the bending edges 87 the lower die is cut away as at 88 to allow clearance for said short, wide lip of the large end or sprocket bar. The punches 86 are spaced apart a distance about equal to the width of the 65 long, narrow lip of the large end or

sprocket bar in order that said long, narrow lip can clear said punches. The working faces 89 of the punches 86 and the cut-away portions 88 are also of part-circle configuration. During the bending operation the working faces 89 engage the inner face of the already formed short, wide lip of the large end or sprocket bar, and the front ends of the link side bars are at the bending edges 87. Clearly, the flat surfaces 84 and 85 cooperate to insure the position of each link blank in the fourth set of dies during the bending operations as described, and at the finish of the operation in the fourth set of dies, said flat surfaces 84 and 85 are all in engagement with the side bars, the surfaces 84 being above said side bars and the surfaces 85 being below them. It will be evident that the punches 80 and 86 engage parts of the inner faces of the wide end bars of the link blank beyond the width of the narrow lips thereof, and that this engagement will be sufficient in cooperation with the bending edges of the lower die, to put bends in the extremities of both side bars. See Figs. 4, 5, 6 and 7. The upper die of the fourth set is, naturally, cut away to be clear of the upwardly thrown narrow lips. See Figs. 4 and 5.

The fifth set of dies, indicated 43, may include the assembling elements.

The upper die 44 of the fifth set of dies includes a part-circle surface 90, preferably less than a half-circle, and the lower die 45 of the fifth set includes a complementary part-circle surface 91 in advance of which is a spacing mandrel 92. When a link blank reaches the dies of the fifth set it is positioned upon the lower die thereof in such manner that the short, wide lip of the sprocket bar rests in the part-circle surface 91, just back of the mandrel 92, and, evidently, when the dies of the fifth set operate, the part-circle surfaces 90 and 91 cooperate to roll the long, narrow lip of the sprocket bar about the small end bar or pintle of a preceding link. See Fig. 4. The spacing mandrel 92 is for the purpose of defining the detaching slot present in the finished chain. The upper and lower dies of the fifth set of dies include recesses, denoted 93 and 94, respectively, allowing clearance for the already formed and positioned small end bar or pintle when the dies of the fifth set are performing their function, and flat surfaces of the dies between the part-circle surfaces and recesses insure the position of the blank while the dies are operating.

Numerical 95 denotes a strip guide for centering the metal strip and causing it to be properly fed across the lower die of the first set of dies, denoted 39. This guide may be of any construction suiting it to its purpose. As disclosed, it consists of a piece 96 of metal the upper face 97 of which is in the horizontal 130

plane of the working face of the lower die of the first set of dies, and a piece 98 of metal the lower face of which rests upon the flat face 97 and has a groove 99 providing a slot 5 between said pieces 96 and 98. Screw bolts 100 securing both pieces of metal to the die bed 38 complete the construction.

Numeral 101 indicates a stop for the metal strip which is positioned between the second 10 and third sets of dies. The purpose of this stop is to arrest the advance of the strip upon each actuation of the strip feeding mechanism so that the blanks which are severed will be uniform length and so that the scoring 15 operations will be accurately and similarly situated on all of the blanks. The stop 101 may be an L-shaped member as disclosed secured to the die bed 38 as at 102 and having a vertical forward face 103 extending 20 transversely of the line of feed of the strip and at the elevation of said line of feed. See Figs. 1, 4, 5 and 7.

A transfer slide 104, beneath the working portion of the stop 101 and above the lower 25 dies of the second to the fifth sets of dies, is for the purpose of advancing the severed blanks step by step, from work station to work station; that is, from the second to the third, from the third to the fourth, and from 30 the fourth to the fifth set of dies, in the machine. The transfer slide and its actuating mechanism will be most clear from Figs. 1, 4, 5, 6, 7, 8 and 9.

105 is a bar suitably mounted in the die bed 35 38 to be longitudinally reciprocatable, and 106 is a plate fixed to said bar as at 107 and including severed-blank-receiving openings 108, 109, and 110. The plate 106 is normally positioned as disclosed in Figs. 4, 5 and 7, to 40 situate the opening 108 directly above the lower die of the second set of dies 40, the opening 109 directly above the lower die of the third set 41, and the opening 110 directly above the lower die of the fourth set 42. The 45 openings 108 and 109 are rectangular and are of dimension to nicely receive the severed blanks and upper dies and to allow free passage of the blanks and upper dies through the openings, each of said openings 108 and 109 being bounded by side walls 111, a rear wall 50 112, and a front wall 113. The opening 110 is similar to the openings 108 and 109 with the exception that said opening 110 has no front wall. Desirably, the plate 106 is closely adjacent to or contiguous with the upper flat faces 55 of the lower dies, and reciprocation of the bar 105 causes said openings of said plate 106 to be moved longitudinally of the line of feed of the metal blanks. The opening 108 is adapted to receive each blank as soon as severed by the upper die of the second set and the lower die of the first set of dies in the manner 60 already described, allowing said blank to drop to the lower die of the second set. When 65 a blank has been operated upon by the dies

of the second set, it is positioned in the opening 108 of the transfer slide. Forward reciprocation (toward the left as disclosed in Figs. 4, 5 and 7) of the transfer slide with plate 106 is adapted to move said opening 108 70 to position directly above the lower die of the third set of dies, whence the blank at the time in said opening 108 is adapted to fall to said lower die of the third set. Then, when a blank has been operated upon by the dies of the third set, it is positioned in the opening 109 of the plate 106, the slide having in the meantime returned to its normal position, and upon advancement of the plate 106 the blank is carried in said opening 109 from said third set to 75 the fourth set and allowed to engage the lower die of said fourth set. When a blank has been operated upon by the dies of the fourth set, it is positioned in the opening 110 of the plate 106, the slide having returned to normal position, and upon advancement of the plate the blank is carried to the lower die of 80 the fifth set of dies. It is to be understood of course, that each forward reciprocation of the transfer slide carries a severed blank from the second to the third, from the third to the fourth, and from the fourth to the fifth set of dies, the rearward reciprocations of the transfer slide being accomplished at a time and in 85 a manner to be clear of the working elements of the upper dies and of the severed blanks themselves. Mechanism to be described operates with the transfer slide to allow the blanks to pass from the openings 108, 109 and 110 to enter the lower dies, and to elevate or 90 eject the blanks from the lower dies and place them in said openings after said blanks are operated upon.

Cap plates 114 secured upon the die bed 38 as by screws 115 hold the bar 105 in its longitudinal way 116 in said die bed (see Figs. 7, 95 8 and 9).

The necessary and proper reciprocation of the transfer slide can be accomplished in any convenient manner. As disclosed more 100 clearly in Figs. 6, 7, 8, 9 and 10, 117 is a link pivoted as at 118 upon the carrier for the upper or movable dies. 119 is a bell crank lever pivoted upon the die bed 38 as at 120. An arm 121 of the bell crank lever is pivoted 115 to the link 117 as at 122, and an arm 123 of said bell crank lever engages the transfer slide. 124 is a cut-away portion of the bar 105 which cut-away portion is bounded at front by an oblique surface 125 and at rear 120 by an arc-shaped surface 126, and 127 is an opening in a side edge of the plate 106 directly above the cut-away portion 124, said opening having a front wall 128 and a rear wall 129. The outer end 130 of the arm 123 of the bell 125 crank lever is arc-shaped and adapted to ride over the surface 126 of the bar without imparting movement to said bar, and the outer end portion of said arm 123 is of dimension to enter the opening 127 in the plate 106. De- 130

sirably, the side edges of the arm 123 adjacent to the outer end 130 are rounded as at 131. In Fig. 9 the carrier 37 is disclosed in its lowest position, the upper and lower dies engaging each other as in Fig. 4. At this time the transfer slide is in its normal, rearward position. As the carrier is elevated with the vertically reciprocatable slide 5, the arm 123 of the bell crank lever rides upwardly over the rearward arc-shaped surface 126 of the bar 105 imparting no movement to said bar until the upper dies have been elevated above the plate 106 of the transfer slide and until the upper die of the second set is above the plane of the strip of metal, it being understood that in being depressed said upper dies have passed through the openings 108, 109 and 110 in the plate 106 to act upon severed blanks supported by the lower dies. Then as the arm 123 leaves the rearward surface 126 of the cut-away portion of the bar 105 and the slide 5 is further elevated, the free end portion of said arm 123 enters the opening 127 in the plate 106 and engaging the forward wall 128 of said opening moves the slide to its forward or advanced position, at which time the arm 123 engages the forward surface 125 of the cut-away portion of the bar. See Fig. 10. As the slide 5 with carrier again comes down, the arm 123 engages the rearward wall 129 of the opening 127 and carries the transfer slide back to its normal position, the opening 108 reaching its rearward or normal position before the link blank is severed from the strip of metal. As the slide 5 thence descends to its lowest position the working operations upon the link blanks are performed, while the arm 123 is moving downwardly over the rearward arc-shaped surface 126 of the bar 105 without disturbing the position of the bar. It will be evident that the transfer slide moves forwardly once and rearwardly once for each working operation of the upper and lower dies, upward movement of the slide 5 with the carrier 37 advancing the transfer slide after the upper dies have receded from the openings 108, 109 and 110 of the transfer slide, and downward movement of the slide with carrier returning the transfer slide to normal, rearward position before the upper dies have reached the elevation of the transfer slide—in fact, before the upper dies of the second set 40 has severed a link blank. The rearward arc-shaped surface of the cut-away portion of the bar 105 provides a dwell cooperating with the outer end of the arm 123 to hold the transfer slide at the extreme of its movement when in rearward position, said transfer slide remaining stationary in rearward or normal position when the carrier 37 is at or near its depressed position. The plate 106 can be cut away (as at 132 between the openings 109 and 110 to clear the free crimped end of the long, narrow lip of the large end or sprocket bar upon the rearward movement

of the transfer slide) at any locations where this is desirable or necessary. See Figs. 4 and 5.

The mechanism for ejecting the severed blanks from the lower dies of the second, third and fourth sets elevates said blanks to the openings 108, 109 and 110, respectively, after they have been operated upon and while the transfer slide is in its normal, rearward position, before said transfer slide is moved forwardly, said mechanism holding each blank elevated just above the plane of the flat upper face of the block 51 until the blank is beyond the lower die from which fed, and preferably, the ejecting mechanism remains in the elevated position of the blanks until the transfer slide reaches its forward position, receding at this time to normal position to allow the blanks to enter the lower dies of the third, fourth and fifth sets of dies, respectively, to receive them for a working operation. That is to say, the severed blanks from the lower dies of the second, third and fourth sets of dies are allowed to enter the lower dies of the third, fourth and fifth sets of dies, respectively, when the transfer slide is in its farthest advanced position and the slide 5 is up, said transfer slide then returning to its rearward or normal position as the upper dies move downwardly, and said upper dies passing afterward through the openings 108, 109 and 110 on their way to operate. The mechanism for ejecting the blanks from the lower dies of the second, third and fourth sets also includes devices for ejecting the blanks from the lower die of the fifth or assembling set of dies after they are operated upon and before the connected chain is fed ahead in a manner to be described, said devices working in unison with the remainder of the blank ejecting mechanism, allowing the severed blanks to enter the lower die of the fifth set for a working operation, and holding the assembled blanks elevated until clear of the spacing mandrel 92.

The severed-link-blank ejecting or elevating mechanism is best disclosed in Figs. 1, 4, 5, 7, 8, 11, 12 and 13. 133 and 134 denote spaced apart bearing brackets secured upon the bottom of the machine frame, the bracket 133 being attached as at 135 beneath the upright 2, and the bracket 134 being attached as at 136 beneath the working dies. A shaft 137 mounted in said brackets 133 and 134 fixedly carries a lever 138 upon its end portion at the fly wheel side of the machine (see Figs. 1, 11 and 12). 139 is a connecting rod pivoted at its lower end 140 to the free end of the lever 138 and having a forked upper end portion 141 which is situated upon the main shaft 8, the connecting rod 139 being adjustable lengthwise. The upper end portion 141 is positioned between the upright 2 and a box cam 142 fixed upon said main shaft, and said upper end portion of the connecting

rod has a stud carrying a roller 143 adapted to ride in a cam path 144 of said box cam. The shaft 137 also fixedly carries a lever 145 upon its end portion beyond the bearing bracket 134. 146 is a guide upon the bracket 134 for a vertically reciprocatable slide 147 having a slot 148 which receives the free end of the lever 145 (see Figs. 12 and 13). The levers 138 and 145 are at opposite sides of the shaft 137, so that when the lever 138 is depressed, the lever 145 with slide 147 is elevated, and vice versa. The slide 147 includes actuating members 149 associated with said slide in any suitable manner and adapted to engage link ejectors 150 slidably vertically in openings 151 through the die bed 38, the anvil plate 50, and the lower dies of the second, third, fourth and fifth sets of dies, a coil spring 152 upon the lower end portion 20 of each ejector 150, between the bottom of the die bed 38 and a collar 153 normally holding said ejectors in their lowermost positions. As disclosed, there are three ejectors 150 for elevating the blanks from the lower die of the second set of dies 40, one being adapted to engage the lower face of the metal to provide the small end bar or pintle of the link at the midwidth thereof, and two being in transverse alignment and adapted to engage 25 the lower face of the metal for the short, wide lip of the large end or sprocket bar adjacent the side edges of the blank. There are four ejectors for elevating the blanks from the lower die of the third set 41, two rearward 30 ones and two forward ones adapted to engage the blank side bars. There is one ejector for elevating the blanks from the lower die of the fourth set 42 which includes a member 154 having a flat upper face between the flat surfaces 85 adapted to engage the lower surfaces of the formed end bars of the blank. There are four ejectors for elevating the blanks from the lower die of the fifth set 43, two rearward ones and two forward ones 35 adapted to engage the formed end bars at spaced apart locations. Any other convenient arrangement of ejectors 150 not interfering with the operations of the working dies can be employed, those shown being suitable. As will be clear from Figs. 4, 5, 11 and 40 45 50 55 60 65 70 75 80 85 90 95 100 105 110 115 120 125 130

It will be evident that the time of lifting of the ejectors 150 and the interval said ejectors are held in raised position will depend upon the construction of the cam path of the box cam, and this construction will be that to accomplish the result as already hereinbefore stated.

Referring to Figs. 4 and 5, it will be apparent that the distances the severed blanks are lifted to be removed from the different lower dies must be variable. To accomplish lifts of variable distance the actuating members are initially set at greater or less distance from the ejectors. See Fig. 4. For accuracy, the members 149 are adjustably associated with the slide 147 as indicated at 156.

Mechanism is employed for extracting and guiding the formed and coupled links out of the machine. This mechanism may be of any suitable character. As disclosed, 157 denotes a chain guide comprising a horizontal plate 158 having its inner end portion resting upon the die bed 38 and its outer end portion projecting into an opening through the adjacent wall of the main frame of the machine, and a guiding member 159 upon said plate, screws 160 holding said plate 158 and member 159 to the die bed and to each other. The guiding member is longitudinally grooved and recessed as indicated at 161 to constitute a guideway for the chain. 162 is a sprocket wheel projecting through a longitudinal slot 163 in the outer end of the plate 158, said sprocket wheel being free to rotate upon a shaft 164 in spaced bearing lugs 165 upon the die bed 38. The upper face of the plate 158 is flat and is at about the elevation of the spacing mandrel 92, the outer end of said upper face being rounded as at 166 adjacent the sprocket wheel. 167 is a ratchet wheel free to rotate upon the shaft 164. The sprocket wheel 162 and said ratchet wheel 167 are integral with each other, 168 denoting a cylindrical connector upon the shaft 164 and between said wheels. As shown, the unit consisting of the sprocket wheel, the cylindrical connector, and the ratchet wheel approximately fills the space between the bearing lugs 165, which lugs locate said unit transversely of the machine frame. 169 is a pawl pivotally connected upon the forward end portion of the bar 105 as at 170, a spring 171 urging said pawl 169 into engagement with the ratchet wheel 167 (see Figs. 7 and 9). Upon each forward movement of the transfer slide with bar 105, the pawl 169 is adapted to engage a tooth of the ratchet wheel and rotate the unit consisting of the ratchet wheel, the connector and the sprocket wheel ahead one step, so that the feeding ahead of the connected chain is accomplished in synchronism with the feeding ahead of the severed blanks, as well as the strip of metal. Upon reverse or rearward movements of the bar 105 the pawl slides over the teeth of the ratchet wheel. 172 is a spring having one of its ends 173 secured to the die bed 38 and its other end 174 bearing against the teeth of the sprocket wheel 162 to offer a frictional resistance to the rotation of the unit consisting of the sprocket wheel, connector and ratchet wheel.

Any suitable mechanism may be employed for the purpose of correcting the size and pitch of the chain links. The size and pitch correcting mechanism is indicated as a whole 5 by the reference numeral 175. Of this mechanism, 176 is an arm extending forwardly from and preferably detachably secured, as at 177, to the carrier 37. This arm 176 has secured to it, as at 178, a downwardly extending finger 179 which is pointed at its lower end as indicated at 180, the rear surface 181 of the said pointed finger being shorter than and at greater inclination to the horizontal than the front surface 182 of the 10 said finger. This finger 179 is arranged to enter the sprocket opening in the last link but one of the links formed in the machine. 183 is an obliquely disposed block or finger secured, as at 184, in an oblique way 185 at the 15 front of the arm 176. The block or finger 183 extends downwardly beneath the arm 176, as indicated at 186, and is adapted to enter the sprocket opening in the link next preceding the link entered by the finger 179. 20 187 is a forward vertical face of the block or finger 183 rounded somewhat at its lower end and 188 is a horizontal face thereof. 189 is an adjusting screw fitted in the arm 176 and adapted to engage the upper oblique face 25 190 of said block or finger 183. The purpose of said screw is to adjust, in cooperation with the screw bolt 184, the block or finger 183 downwardly or upwardly, from or toward the finger 179. In operation, the finger 179 enters 30 an opening 191 in the plate 158. See Fig. 4. 35

The distance between the front wall 187 of the block or finger 183 and the rear wall 181 of the finger 179 remains substantially constant when the machine is in operation. 40 If a link is shorter in pitch than it should be, these sizing fingers bring it up to proper pitch by stretching it. In practice, it is desirable to form and arrange the working dies for making of the desired and proper pitch, chain 45 links from the thinnest sections of the strip of metal used, depending upon the stretcher or pitch correcting device 175 to draw the links formed from the thicker sections of the strip of metal up to gage.

50 The operation of the machine will be readily understood. A strip of metal 36 is directed through the feed mechanism until the gripping jaws 26', 27' of said feed mechanism can engage it. Power is then applied 55 through the counter shaft 9 to actuate the machine. The strip is guided and centered by the guide 95 so as to lie properly between the upper and lower dies of the first set of dies 39. The slide 5 with carrier having 60 working dies descends and a section of metal to form a link blank is first acted upon by the scoring knives or chisels which completely outline the blank, producing the longitudinal score lines 192, the short transverse 65 score line 193, and the longer transverse

score line 194, as shown in Figs. 14 and 15. The upper die is then elevated and the feed mechanism operates to feed the stock forward one step, the feeding commencing just after the upper die of the second set 40 is above the plane of the strip metal. This brings the transverse score line 194 to the transverse severing edge 61 of the lower die of the first set of dies 39. The slide descends and the severing edges 60 and 61 cooperate to sever the blank which immediately falls (through the opening 108 of the transfer slide at the time in its rearward or normal position immediately above the lower die of the second set of dies 40) into the lower die of said second set. As the slide descends further, the dies of the second set cooperate to break the metal of the severed blank along the line of score 193 and portions of the line of score 192 and to remove the long, narrow lip of the large end or sprocket bar out of the plane of the link blank as indicated at 195. When the slide is next elevated, the ejectors 150 first lift the severed blank out of the lower die of the second set 40 and position said blank in the opening 108 in the plate 106 of the transfer slide, then said slide advances said severed blank to the lower die of the third set of dies 41, and the objectors recede to allow the blank to enter said lower die of the third set. As the slide 5 descends the transfer slide moves from its forward to its normal, rearward position, and the upper die of the third set passes through the opening 109 of the plate 106 of the transfer slide and cooperates with the lower die of said third set in operating upon the blank. The combined action of the working elements of the third set is to break the metal along portions of the lines of score 192 to define the short, narrow lip of the small end bar or pintle; to give said small end bar or pintle its final curvilinear form as indicated at 196; to give the short, wide lip of the large end or sprocket bar its final curvilinear form as indicated at 197; and to crimp to curvilinear form the free end of the long, narrow lip of said large end or sprocket bar as indicated at 198. As the slide again goes up, the blank is fed to the fourth set of dies 42 in the manner as already described, to be there operated upon by the working elements of said fourth set, the upper die of the fourth set passing through the opening 110 on its way toward the lower die. The combined action of said working elements of the fourth set is to position the small end bar or pintle at right-angle to the link side bars as indicated at 199, and to throw the short, wide lip of the large end or sprocket bar downwardly and the long, narrow lip thereof upwardly to thus place the large end or sprocket bar in position for the final assembling operation as indicated at 200. As the slide again goes up the blank is fed to the fifth set of dies 43 in the same man- 115 120 125 130

ner as from the second to the third and from the third to the fourth sets. The combined action of the working elements of the fifth set is to curl or roll the metal of the long, narrow lip of the large end or sprocket bar into cylindrical shape and about the small end bar or pintle of the next preceding link as indicated at 201, the free end of said long, narrow lip having previously been crimped in the third set of dies. The slide is then elevated and the extracting mechanism pulls the completed link out of the stationary die of the fifth set and advances it into position in which its small end bar or pintle is properly centered relative to the forming elements 90 and 91 so that the large end or sprocket bar of the next link in the series will be formed around it and these two links thus assembled. One sprocket tooth of the sprocket wheel 162 projects through a formed link in the guide 157 and when the transfer slide with bar 105 is advanced, the pawl 169 engages a tooth of the ratchet wheel 167 and turns the unit consisting of the sprocket wheel, the connector and the ratchet wheel, the rotation of the sprocket wheel being sufficient to advance a formed link one step. When the slide next descends the pitch correcting finger 179 enters the next to the last formed link, its surface 181 engages the large end or sprocket bar of the last formed link and moves rearward the last formed link, positioning said link with its small end bar overlapping the forward end of the next succeeding link and properly centered relative to the forming elements 90, 91. The stretching and pitch correcting finger 183 enters the link coupled to the link entered by the finger 179, and these two fingers cooperate to correct the pitch of the links. At the next elevation of the slide the extractor operates to advance the formed link another step, and this step by step advancing of the formed links, as well as of the strip of metal and severed blanks, within the machine is continued, one link at a time being delivered from the machine.

The advantages of the present method and apparatus over disclosures such as that of the Osswald patent identified and over dies operated on independent presses have already been hereinbefore set forth.

Many alterations in the construction and many apparently widely differing embodiments and applications of the invention will suggest themselves to those skilled in the art of making sheet metal chain links and chain making machines without departing from the scope and spirit thereof. The disclosure and description herein are purely illustrative, and are not intended to be in any sense limiting.

What I claim is:

1. In a machine for making chain links, means for removing sections of similar shape one by one from a strip of metal to provide

blanks, a set of working elements adapted to successively engage each blank, means for delivering the blanks one at a time to said mentioned set of working elements, means for removing each blank from said mentioned set of working elements after an operation is performed, means for feeding the blanks one at a time to a different set of working elements, and means for assembling the blanks into a chain.

2. In a machine for making chain links, means for removing sections of similar shape one by one from a strip of metal to provide blanks, a set of working elements adapted to successively engage each blank, means for delivering the blanks one at a time to said mentioned set of working elements, means for removing each blank from said mentioned set of working elements after an operation is performed, a second set of working elements adapted to successively engage each blank, means for depositing the blanks one at a time to said second set of working elements, means for removing each blank from said second set of working elements after an operation is performed, and means for assembling the blanks into a chain.

3. In a machine for making chain links, means for removing sections of similar shape one by one from a strip of metal to provide blanks, a set of working elements adapted to successively engage each blank, means for depositing the blanks one at a time to said mentioned set of working elements, means for removing each blank from said mentioned set of working elements after an operation is performed, a plurality of other sets of working elements adapted to successively and independently engage each blank, means for delivering the blanks one at a time to each of said other sets of working elements, means for removing each blank from each of said other sets of working elements after an operation is performed, and means for assembling the blanks into a chain.

4. In a machine for making chain, means for feeding a strip of metal ahead step by step, means for removing sections one by one from the strip to provide blanks, a set of working elements adapted to successively engage each blank, means for delivering the blanks one at a time to said mentioned set of working elements, means for removing each blank from said mentioned set of working elements after an operation is performed, other sets of working elements, means for successively feeding the blanks one at a time to each of said other sets of working elements, means for removing the blanks from each other set of working elements after an operation is performed, assembling elements, means for successively feeding the blanks one at a time to said assembling elements, and means for removing the finished links from said assembling elements.

5. In a machine of the character described, a plurality of sets of working elements each adapted to perform an operation upon a link blank, a transfer slide adapted to transport link blanks from one set of working elements to another, and mechanism for ejecting the link blanks from the working elements of the different sets after an operation upon said blanks and for locating said blanks in said transfer slide to be fed ahead. 70
- 10 6. In a machine of the character described, a plurality of sets of working elements each adapted to perform an operation upon a link blank, a transfer slide adapted to transport link blanks one at a time from one set of working elements to another, and mechanism cooperating with said transfer slide adapted to allow the blanks to be removed from the slide to enter the working elements of the different sets for an operation upon said blanks, to eject said blanks from said working elements after an operation upon the blanks, and to locate said blanks in said transfer slide to be fed ahead. 75
- 15 20 7. In a machine of the character described, a stationary member, a movable member, a plurality of sets of working elements each consisting of a die upon said stationary member and a die upon said movable member, each set of working elements being adapted to perform a transforming operation upon a chain link blank, a transfer slide adapted to transport blanks one at a time from one set of working elements to another, and mechanism 80
- 25 30 35 40 45 50 55 60 65 70 75 80 85 90 95 100 105 110 115 120 125 130
- cooperating with said transfer slide adapted to allow the blanks to be removed from the slide to enter the working elements of the different sets for an operation upon said blanks, to eject said blanks from said working elements after an operation upon the blanks, and to locate said blanks in said transfer slide to be fed ahead. 100
8. In a machine of the character described, a stationary member, a movable member, a plurality of sets of working elements each consisting of a die upon said stationary member and a die upon said movable member, each set of working elements being adapted to perform a transforming operation upon a chain link blank, a transfer slide adapted to transport blanks one at a time from one set of working elements to another, means for actuating said transfer slide, mechanism cooperating with said transfer slide adapted to allow the blanks to be removed from the slide to enter the working elements of the different sets for an operation upon the blanks and to enter an assembling element of said assembling set for an operation upon the partially completed links, to eject said blanks from said working elements after an operation upon said blanks and said partially completed links from said assembling element after an operation upon each partially completed link, and to locate said blanks in said transfer slide to be fed ahead, means for actuating said transfer slide and its cooperating mechanism, and means for feeding said strand of chain ahead step by step. 110
9. In a machine of the character described, a stationary member, a movable member, a plurality of sets of working elements each

- consisting of a die upon said stationary member and a die upon said movable member, each set of working elements being adapted to perform a transforming operation upon a chain link blank, a transfer slide adapted to transport blanks one at a time from one set of working elements to another, mechanism cooperating with said transfer slide adapted to allow the blanks to be removed from the slide to enter the working elements of the different sets for an operation upon said blanks, to eject said blanks from said working elements after an operation upon the blanks, and to locate said blanks in said transfer slide to be fed ahead, and means for actuating said movable member, said transfer slide, and said mechanism cooperating with said transfer slide in synchronism. 85
10. In a machine for making chain, a stationary member, a movable member, means for actuating said movable member, a plurality of sets of working elements each consisting of a die upon said stationary member and a die upon said movable member, each set of working elements being adapted to perform a transforming operation upon a chain link blank to transform it into a partially completed link, a set of assembling elements consisting of a die upon said stationary member and a die upon said movable member, said assembling elements being adapted to connect each partially completed link as formed to a strand of chain, means for feeding a strip of metal ahead step by step, cooperative means upon said stationary and movable members for severing sections from a strip one by one to provide chain link blanks, a transfer slide adapted to transport blanks one at a time from one set of working elements to another and from the last set of working elements to the set of assembling elements, mechanism cooperating with said transfer slide adapted to allow the blanks to be removed from the slide to enter the working elements of the different sets for an operation upon the blanks and to enter an assembling element of said assembling set for an operation upon the partially completed links, to eject said blanks from said working elements after an operation upon said blanks and said partially completed links from said assembling element after an operation upon each partially completed link, and to locate said blanks in said transfer slide to be fed ahead, means for actuating said transfer slide and its cooperating mechanism, and means for feeding said strand of chain ahead step by step. 95
11. The combination as specified in claim 10, wherein the means for actuating the movable member, the means for feeding the strip of metal ahead step by step, the means for actuating the transfer slide and its cooperating mechanism, and the means for feeding the 120

- strand of chain ahead step by step are all interconnected to be in synchronism.
12. In a chain-making machine, means to feed a strip of metal, means to sever link blanks from said strip, a transfer slide having a plurality of openings therein to receive said blanks, sets of dies registering with said openings and adapted to perform link-forming operations upon blanks, each set of dies comprising a relatively stationary and a relatively movable die, a carrier for said movable dies, means to move said carrier with its dies towards and away from said stationary dies, a bell crank lever mounted on a fixed pivot, a link connecting one arm of said lever to said carrier and adapted to rock said lever upon movement of said carrier, and means on said slide engaged with the other arm of said lever to cause reciprocation of the slide as the lever is rocked on its pivot by movement of the carriage.
13. In a chain-making machine, means to feed a strip of metal, means to sever link blanks from said strip, a transfer slide having a plurality of openings therein to receive said blanks, sets of dies registering with said openings and adapted to perform link-forming operations upon blanks, means to move said slide to carry blanks in said openings into registry with other sets of dies, means to discharge the blanks at said other sets, and means to return said slide to initial position.
14. In a chain-making machine, means to feed a strip of metal, means to sever link blanks from said strip, a transfer slide having a plurality of openings therein to receive said blanks, sets of dies registering with said openings and adapted to perform link-forming operations upon blanks, means to move said slide to carry blanks in said openings into registry with other sets of dies, means to discharge the blanks at said other sets, means to return said slide to initial position, means to join links together to form a finished chain, and means actuated by movement of said slide to feed said chain from the machine.
15. In a chain-making machine, a transfer slide having a plurality of spaced openings to receive link blanks, a set of dies registering with each of said openings, and means to move said slide in a straight line to bring at least one of said openings into registry with a different set of dies.
16. In a chain-making machine, a transfer slide having a plurality of spaced openings to receive link blanks, a set of dies registering with each of said openings, and means to move said slide to bring at least one of said openings into registry with a different set of dies, one of said openings being at the end of the slide and being open towards said end, the set of dies registering with said opening being adapted to join together two links of the chain.
17. In a chain-making machine, means to feed a strip of metal, means to sever link blanks from said strip, a transfer slide having a plurality of openings therein to receive said blanks, sets of dies registering with said openings and adapted to perform link-forming operations upon blanks, each set of dies comprising a relatively stationary and a relatively movable die, a carrier for said movable dies, means to move said carrier with its dies towards and away from said stationary dies, and means operated by said movement adapted to actuate said slide to carry blanks in the said openings into registry with other sets of dies and to return the slide to the initial position.
18. In a chain-making machine, means to feed a strip of metal, means to sever link

blanks from said strip, a transfer slide having a plurality of openings therein to receive said blanks, sets of dies registering with said openings and adapted to perform link-forming operations upon blanks, each set of dies comprising a relatively stationary and a relatively movable die, a carrier for said movable dies, means to move said carrier with its dies towards and away from said stationary dies, a bell crank lever mounted on a fixed pivot, a link connecting one arm of said lever to said carrier and adapted to rock said lever upon movement of said carrier, and means on said slide engaged with the other arm of said lever to cause reciprocation of the slide as the lever is rocked on its pivot by movement of the carriage.

Signed at Bridgeport, in the county of Fairfield, and State of Connecticut, this 20th day of August, A. D. 1926.

SYLVANUS D. LOCKE.
